UNITED STATES PATENT OFFICE.

EDWARD HENRY MURPHY, OF ST. PAUL, MINNESOTA.

THERMOSTATIC VALVE.

No. 837,099.

Specification of Letters Patent.

Patented Nov. 27, 1906.

Application filed July 10, 1905. Serial No. 268,956.

To all whom it may concern:

Be it known that I, EDWARD HENRY MURPHY, a citizen of the United States, residing at St. Paul, county of Ramsey, State of Minnesota, have invented a certain new and useful Improvement in Thermostatic Valves; and I declare the following to be a full, clear, and exact description of the invention, such as will enable others skilled in the art to 10 which it pertains to make and use the same, reference being had to the accompanying drawings, which form a part of this specification.

My invention relates in general to steam-heating systems, and more particularly to 15 thermostatic valves for automatically controlling the communication between radiators and a return-pipe, so that the water of condensation and air may be removed from 20 the radiators while the steam will be prevented from entering the return-pipe.

It is desirable that the pressure in steam-heating systems should be maintained below 25 that of the atmosphere in order that the steam may be more quickly generated and circulated throughout the system at a low degree of pressure, thereby economizing in fuel consumption. This desirable result is 30 accomplished in some systems by thermostatic valves or traps interposed between the outlet-couplings of the radiators and a return-pipe into which the air and water of condensation are automatically discharged and from which the air is exhausted by suitable mechanism—such, for instance, as a 35 vacuum-pump.

The primary object of my invention is to provide a thermostatic valve for a steam-heating system such as that above referred 40 to which will require no adjusting and which will remain open at all temperatures below a predetermined degree and will be closed at all temperatures above such predetermined degree.

45 A further object of my invention is to provide a thermostatic valve which will be simple in construction, inexpensive in manufacture, and efficient in operation.

The embodiment of my invention herein 50 disclosed may be generally described as comprising a casing, a coupling for connecting the casing to the outlet from a radiator, a coupling for connecting the casing to a return-pipe, a valve-seat in said casing inter-

mediate of said couplings, a valve co-operating with said seat, a valve-stem connected to said valve, a U-shaped tube through the opposite ends of which the valve-stem loosely passes, an expansible fluid within said tube, means for retaining one end of said tube in engagement with the valve, means for securing the other end of said tube to the casing, and a second valve controlling a by-pass around said valve-seat.

My invention will be more fully described 65 hereinafter with reference to the accompanying drawings, in which the same is illustrated as embodied in a convenient and practical form, and in which—

Figure 1 is a vertical central sectional view 70 on line 1 1, Fig. 2; Fig. 2, a horizontal sectional view on line 2 2, Fig. 1; Fig. 3, a detail sectional view on line 3 3, Fig. 1.

The same reference characters are used to designate the same parts in the several figures of the drawings.

Reference-letter A indicates a casing of any suitable size and shape. The casing is provided with a circular opening around which projects an interiorly-screw-threaded 80 flange a'.

A' indicates a cap provided with an exteriorly-screw-threaded flange adapted to engage within the flange a', and thereby detachably secure the cap to the casing. 85

a³ indicates an exteriorly-screw-threaded coupling projecting from the casing A around an opening through which the interior of the casing communicates with a radiator.

B indicates a coupling adapted to be secured to the outlet-opening from a radiator and to rest against the end of the coupling a³. The coupling B is provided with a shoulder b, projecting around the same. 90

b³ indicates an interiorly-screw-threaded 95 ring surrounding and engaging the coupling a³ and provided with an inturned flange bearing against the shoulder b, thereby securing the coupling B to the coupling a³.

a⁴ indicates an interiorly-screw-threaded 100 coupling projecting from the casing A and adapted to be secured to a return-pipe of a steam-heating system.

a indicates a valve-seat formed integrally with the casing and interposed between the 105 inlet-coupling a³ and the outlet-coupling a⁴.

d indicates a valve adapted to co-operate with the valve-seat a and provided with a

valve-stem D. The upper end of the valve-stem D extends within a tubular guide d' , depending from the cap A'.

C indicates an expandable member, preferably composed of a tube, within which is located a volatile fluid. The member C is preferably U-shaped and is provided at one end with a ring c' , loosely surrounding the valve-stem D adjacent the valve d . A pin d^2 extends through the valve-stem D and retains the ring c' at all times in engagement with the valve. The upper end of the member C is provided with a ring c' , through which the valve-stem loosely passes. The ring c' is immovably secured to the casing in any suitable manner—as, for instance, by a screw-threaded rod E, which extends through the casing and into a socket c , formed in the ring c' , thereby retaining the ring against the lower end of the tubular guide d' . The casing A is provided with an extension A^2 , within which the expandable member C projects. Guide-ribs a^2 are provided on the inner surfaces of the walls of the portion A^2 of the casing, between which the expandable member extends. a^3 indicates a by-pass around the valve-seat a .

f indicates a valve for controlling the by-pass a^6 . The stem F of the valve f projects to the exterior of the casing and is surrounded by a gland G in screw-threaded engagement with a socket a^5 , formed integrally with the casing.

g indicates packing interposed between the casing and inner end of the gland. The outer end of the valve-stem f' is preferably squared to permit the seating and unseating of the valve through the rotation thereof.

Any suitable volatile fluid may be inclosed within the tube C, preferably, however, a fluid which will vaporize at 212° Fahrenheit, thereby expanding the tube and causing the ends thereof to separate.

The operation of my invention is as follows: When there is no steam in the system, the valve d is held away from the seat a by reason of the expandable member occupying its normal position, such as shown in Fig. 1. The radiator is consequently in communication with the return-pipe, so that water of condensation and air pass through the coupling a^3 into the casing A, thence through the valve-seat a and coupling a^4 to the return-pipe. When steam has been generated in the system, it flows from the radiator to the valve-casing A, where it volatilizes the fluid within the tube C, thereby causing the latter to expand. As the upper end of the tube C is immovably secured to the casing by means of the screw-threaded rod E, the lower end moves downwardly, thereby forcing the valve d against the valve-seat a , so that the flow of steam to the return-pipe is cut off. When the steam is discontinued in the system, the fluid within the tube C condenses, permitting

the tube to return to its normal condition. The contraction of the tube moves its ends together, and as the one end is secured to the valve-casing the other end through engagement with the pin d^2 lifts the valve d away from the seat a , so that water of condensation and air may pass from the radiator to the return-pipe.

From the foregoing description it will be observed that I have invented an improved thermostatic valve which automatically controls the communication between a radiator and a return-pipe, so that water of condensation and air may be expelled from the radiator, while the escape of steam to the return-pipe will be prevented.

While I have shown and described the expandable member as consisting in a tube containing a volatile fluid, yet I do not wish to be understood as limiting myself to such form of expandable member, as it is obvious that a metal spring or loop may be used so constructed as to open and close the valve at a predetermined degree of temperature.

Having now fully described my invention, what I claim as new, and desire to secure by Letters Patent, is—

1. In a thermostatic valve, the combination with a casing, of a valve-seat in said casing, a valve coöperating with said valve-seat, a valve-stem secured to said valve, a tubular guide for said valve-stem, a substantially U-shaped expandable member through the ends of which said stem loosely passes, means for securing one end of said member to said valve-stem, and means for retaining the other end of said member against said tubular guide.

2. In a thermostatic valve, the combination with a casing, of a valve-seat set in said casing, a valve coöperating with said valve-seat, a valve-stem secured to said valve, a tubular guide for said valve-stem, a substantially U-shaped tubular member containing an expandable fluid, means for securing one end of said member to the valve-stem, and means for retaining the other end of said member against said tubular guide.

3. In a thermostatic valve, the combination with a casing, of a valve-seat in said casing, a valve coöperating with said valve-seat, a valve-stem secured to said valve, a U-shaped expandable member through the ends of which said stem loosely passes, means for securing one end of said member to said valve, means for securing the other end of said member to said casing, said casing having a by-pass around said valve-seat, and a second valve controlling said by-pass.

4. In a thermostatic valve, the combination with a casing, of a valve-seat in said casing, a valve coöperating with said valve-seat, a valve-stem secured to said valve, a U-shaped tubular member containing an expandable fluid through the ends of which said stem loosely passes, means for securing one

end of said member to said valve, means for securing the other end of said member to said casing, said casing having a by-pass around said valve-seat and a second valve controlling 5 said by-pass.

5. In a thermostatic valve, the combination with a casing of a valve-seat in said casing, a valve coöperating with said valve-seat, a stem secured to said valve, a substantially 10 U-shaped expansible member through the ends of which said stem loosely passes, a pin extending through said stem retaining one end of said member in engagement with said valve, a rod extending through said casing 15 into engagement with the other end of said member, said casing having a by-pass around said valve-seat and a second valve controlling said by-pass.
6. In a thermostatic valve, the combination with a casing, of a removable cap for 20 said casing, a valve-seat in said casing a valve coöperating with said valve-seat, a valve-stem secured to said valve, a tubular guide for said valve-stem carried by said cap, a 25 substantially U-shaped expansible member

through the ends of which said stem loosely passes, means for retaining one end of said member against said valve, and means for retaining the other end of said member against said tubular guide.

7. In a thermostatic valve, the combination with a casing, of a coupling adapted to connect said casing with the radiator, an outlet-coupling adapted to connect said casing to a return-pipe, a valve-seat in said casing 30 intermediate of said couplings, a valve coöperating with said valve-seat, a valve-stem secured to said valve, a substantially U-shaped expansible member operatively connected to said valve for seating and unseating the 35 same, said casing having a by-pass around said valve-seat, and a second valve controlling said by-pass.

In testimony whereof I sign this specification in the presence of two witnesses.

EDWARD HENRY MURPHY.
